UNITED STATES PATENT OFFICE.

HARRY KING, OF WASHINGTON, DISTRICT OF COLUMBIA.

CARTRIDGE.

SPECIFICATION forming part of Letters Patent No. 236,230, dated January 4, 1881.

Application filed November 18, 1880. (No model.)

To all whom it may concern:

Be it known that I, HARRY KING, a citizen of the United States, residing in the city of Washington, and District of Columbia, have invented certain new and useful Improvements in Cartridges; and I do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

My invention relates to center-fire metallic cartridge-cases for breech-loading fire-arms, in which the percussion-cap is received in a recess in the head and exploded upon an anvil contained in the recess.

Its object is to facilitate the insertion and disengagement of the cap. I accomplish this result by the mechanism illustrated in the accompanying drawings, in which—

Figure 1 is a perspective of the cartridge primed; Fig. 2, a perspective of the cartridge, ejection of the exploded cap being represented; Fig. 3, a longitudinal section through the head of the cartridge-case on line $\alpha\alpha$ of Fig. 7, the guide C being retracted and closed upon the cap, and holding it upon the anvil. Fig. 4 is the same section as Fig. 3, showing the guide C open, protruding, and ejecting the cap. Fig. 5 is a front view of the head of the case, showing the slotted recess, the guide C and the anvil having been removed. Fig. 6 is a front view of the head of the case, showing the slotted recess and anvil, the guide C not being shown. Fig. 7 is a front view of the head of the case, showing guide C and anvil in place. Fig. 8 is a side view of the guide C, with a part in section, the guide being represented open, and supporting, but not grasping, the cap. Fig. 9 is a plan of the blank from which the guide C may be formed. Fig. 10 is a perspective of the anvil.

Similar letters refer to similar parts throughout the several views.

A is a cylindrical metallic cartridge-case. The head of the case A has an exterior central cylindrical recess, B, having in the bottom an oblong rectangular central slot, b.

The anvil, which is shown in Fig. 10, is a

block of metal, consisting of the perpendicular post D, shaped to enter the cap, and its oblong transverse base D'. The anvil is placed within the recess B and rigidly attached to the bottom, the axis of the post D being in the line of the axis of the recess B, and the base D' lying directly across the slot b. The edges of the anvil-post are beveled, as shown in the drawings, to facilitate the passage of the spark to the charge; and the top of the base D' is also beveled to make room within the recess for the projections d of the guide C.

C is a spring guide and carrier for the percussion-cap. It consists of an oblong metallic plate-spring bent at the middle, and having at each end a semicircular jaw or half-ring, c, opposite and corresponding to each other. When the spring-guide C is closed the half-rings c form a cylinder adapted to fit snugly in the recess B and surround and closely grasp a cylindrical percussion-cap, a, making gas-tight joints.

Below the jaws the shafts of the spring-guide C are provided with the rigid projections d, two on each shaft. The projections are toward a common center, and their points constitute a horizontal platform for the cap. Their lower edges are sloped upward to fit over the anvil-base D'.

The blank from which the guide C may be formed (see Fig. 9) shows its shape when flattened out.

The shafts e e of the guide C are adapted to slide and be guided in the slot b. They do not press against the anvil when the cartridge is primed. Thus room, as shown in Figs. 3 and 7, is left for the flash of the fulminate to pass to the charge.

In the order of construction the guide C is first inserted in the recess B and the bend of the shafts e passed through the slot b. The anvil is afterward introduced into the recess B and placed between the shafts e crosswise, and over the slot b, as described.

In operating my invention the spring-guide C is protruded from the recess B by longitudinal pressure from within the cartridge-case, either with the finger or a stick, as shown in Fig. 4 in dotted lines, upon the bend of the spring, the guide C being prevented by the anvil, which lies within its bend, from being

pushed entirely out. As the guide C protrudes the jaws *c c* are pressed apart by the operation of the spring and the pressure of the anvil against the inside of the shafts *e e*. The position of these parts at this stage is shown in Fig. 4. The cap *a* is then dropped within the jaws *c* upon the supports *d*, where it rests loosely, as shown in Fig. 8. Pressure being now applied with the hand to the top of the guide C, containing the cap, the guide and cap are together pushed down into the position shown in Figs. 1 and 3, wherein the cap, as shown in dotted lines in Fig. 3, rests upon the anvil-post D, and the jaws *c c* closely embrace the cap, while they are themselves closely embraced by the walls of the recess B.

After the cartridge has been discharged the cap is removed in the following manner: The spring-guide C is protruded by pressure applied within the case, as described. The cap is raised from the anvil by and upon the ejectors *d* of the guide C as the jaws *c c* recede from each other and release their hold upon the cap. The cap is then tossed out, as shown in Figs. 2 and 4.

The device for carrying and holding the cap is applicable to caps which have anvils attached to them. In that case the post of the anvil D D' is omitted, and the base or cross-piece D' only is used, operating as a stop.

Arms pivoted together at their lower ends may be used, instead of a bent spring, to unite the jaws of the guide C.

The cylindrical shape is given to the jaws 35 of the guide C, both without and within, in

order to conform to the cylindrical shape of the cap and recess B. When the cap or recess has any other figure the shape of the jaws must correspond.

I claim as my invention, and desire to secure by Letters Patent, the following:

1. In a cartridge, the recess B, having a greater diameter than the cap, the space between the cap and the walls of the recess being filled by sliding jaws *c c*, by means of which the insertion of the cap is facilitated all as set forth.

2. In combination with a cartridge provided with the slotted recess B and stop D', the semicircular jaws *c c*, terminating the arms *e*, and adapted to embrace the percussion-cap within the recess, as described.

3. In a cartridge, the combination, with a metallic cartridge-head having the recess I and the slot *b*, of the anvil D D', located as described, and the cap-carrying guide C, having the semicircular jaws *c c* and the projections *d*, all as and for the purpose set forth.

4. In combination with a cartridge provided with the slotted recess B and anvil D D', the semicircular jaws *c c*, terminating a bent spring, and adapted to embrace the percussion-cap within the recess, as described.

In testimony whereof I have affixed my signature in presence of two witnesses.

HARRY KING.
